UNITED STATES PATENT OFFICE.

AUGUSTUS C. SAXTON, OF CHICAGO, ILLINOIS, ASSIGNOR TO H.-R. MANUFACTURING COMPANY, OF CHICAGO, ILLINOIS, A CORPORATION OF ILLINOIS.

LEVER LOCK.

Application filed October 14, 1922. Serial No. 594,441.

My present invention relates more particularly to that class of locks which are applied to the transmission lever to enable the user of a machine to prevent use thereof by an unauthorized person. Among the objects of this invention are to produce a new and more effective actuating mechanism for the lock plunger in a structure of the character described; to so house the actuating 10 spring of the locking member as to minimize the danger of its getting out of order; to dispense, so far as possible, with openings from the exterior to the interior of the locking member in order to minimize to the utmost any possibility of tampering with the lock when locked; and such further objects, advantages, and capabilities as will later more fully appear.

My invention further resides in the combination, construction and arrangement of parts, illustrated in the accompanying drawing, and, while I have shown therein a preferred embodiment I desire the same to be understood as illustrative only and not as 25 limiting my invention.

In the accompanying drawing, Fig. 1 is a broken sectional elevation showing what I now consider the preferred embodiment of my present invention. Fig. 2 is a similar 30 view showing the operative parts in a different position. Fig. 3 is a sectional plan view substantially along the plane indicated by the line 3—3 Fig. 1. Figs. 4 and 5 are perspective views of the lock cylinder and lock plunger, shown in elevation and plan 35 in the preceding views.

Referring more in detail to the annexed drawing, 1 denotes the transmission housing and 2 the transmission lever pivoted in the 40 housing as is usual in structures of this kind. Surrounding and secured to the transmission casing 1, by means of adjustable securing means 4, such as screws or pins, is a sleeve 3 which co-operates with the locking member 5 to prevent the transmission lever 2 from being actuated. Adjustable 45 members 6 pass through the sleeve 3 and abut against the transmission casing 1 so that the sleeve may be properly positioned, laterally, with respect to the transmission lever. After screws 4 and 6 have been properly adjusted they are cut off flush with the surface so as to make it impossible to laterally remove the sleeve 3. This sleeve has in 50 its normally upper end an aperture having

an inwardly inclined beveled surface 7, with which co-operates a similarly bevelled surface on the normally lower face of the locking member 5.

The locking member is provided on one side with a projection 8 having a bore extending therethrough and into the hollow interior of the locking member. This bore 9 serves as a housing for a locking plunger 10 and a lock cylinder 11, the former having a projection 12 extending from the forward face thereof, and adapted to engage in notch 13 in the periphery of a lock sleeve 14. This lock sleeve 14 is longitudinally apertured and adapted to fit closely on the transmission lever 2, being secured in place thereon by any suitable means 15, such as a pin or headless screw. A socket 16 is formed in the normally upper end of lock sleeve 14 for the reception of an actuating spring 17, the purpose of which is to normally hold the locking member 5 in raised position, which it will do when locking plunger 10 is withdrawn so that projection 12 no longer engages notch 13. Locking member 5, fitting 80 sleeve 14 closely, except for a groove 18, slides freely thereon under the influence of spring 17, in one direction, or of pressure exerted thereon in the opposite direction. A projection or screw 19 extends outwardly 85 from sleeve 14 into groove 18 to prevent relative rotation of the sleeve and the locking member 5, while a co-operating projection or screw 20 extends inwardly to engage with projection 19 to limit the upward movement 90 of the locking member when plunger 10 is withdrawn. It is preferable that the notch 13 shall be in the form of a groove having its upper edge or face at substantially a right angle to the axis of the sleeve and its 95 lower edge or face having inclination thereto such that downward pressure on member 5 cannot cause plunger 10 or projection 12 to be bent. The lower face of projection 12 is inclined also to co-operate with the inclined lower face of the notch or groove 13.

A pair of pins 20, surrounded by springs 21, pass through apertures 22 in the locking plunger 10 which slides freely on these pins. Another aperture 23 is provided in plunger 10 for the reception of a projection 24 from the lock cylinder, which projection carries a stem 25 on which is rotatably mounted a roller 26. It will be clear that, as the lock cylinder is turned, the projection 25, 26, co- 110

operating with inclined face 27 of the locking plunger, will cause the plunger to be retracted from its locking position so that lock member 5 will be released and permitted to move upwardly under the influence of spring 17.

In order to prevent this lock from being tampered with, the parts are, so far as practicable, formed of steel, which will be sufficiently hard to render it next to impossible to cut the same by such means as is ordinarily used for this purpose.

It is of course understood that the specific description of structure set forth above may be departed from without departing from the spirit of my invention, as set forth in this specification and the appended claims.

Having now described my invention, I claim:

1. In a transmission locking mechanism, a sleeve having a bore in which is secured a transmission lever, said sleeve having a notch in the periphery thereof for the reception of a lock plunger, and a recess in one end surrounding the bore of the sleeve for the housing of an actuating spring, a spring housed in said recess, and a lock member enclosing and slidable on said sleeve and serving as a closure for said spring housing, said spring adapted to move said lock member from locking position.

2. In a transmission locking mechanism, a sleeve adapted to be secured to a transmission lever, said sleeve having a notch in the periphery thereof for the reception of a lock plunger and a depression in its upper end surrounding the longitudinal aperture of the sleeve for the housing of an actuating spring, a spring housed therein, and a lock member enclosing and slidable on said sleeve

and serving as a closure for said spring housing, said spring adapted to move said lock member from locking position, said member, aside from the opening for the reception of the transmission lever, being imperforate on its upper surface.

3. In a lock, a relatively fixed notched sleeve adapted to be secured to a transmission lever, said sleeve having a peripheral groove therein, a locking member slidable longitudinally on the sleeve and having locking means to engage the notch of said sleeve, said locking member having a longitudinal groove internally thereof, and co-operating projections on the exterior of the sleeve and interior of the locking member respectively adapted to engage within the longitudinal groove to limit the relative longitudinal sliding movement of the sleeve and locking member and prevent said locking member from rotating.

4. In a transmission locking mechanism, a sleeve adapted to be secured to a transmission lever, said sleeve having a notch in the periphery thereof for the reception of a lock plunger, and a depression in one end surrounding the longitudinal aperture of the sleeve for the housing of an actuating spring, a lock actuating spring housed therein, and a lock member enclosing and slidable on said sleeve and serving as a closure for said spring housing, in combination with an adjustably mounted sleeve surrounding and secured to the transmission housing and having in its upper end an opening for the reception of the lock member when the latter is moved into locking position.

In witness whereof, I hereunto subscribe my name to this specification.

AUGUSTUS C. SAXTON.
